CLAIM

The ornamental design for an instrument for measuring fat in the human body, as shown and described.

DESCRIPTION

FIG. 1 is a perspective view showing the top, front edge and right side right side edge of our new design for an instrument for measuring fat in the human body;

FIG. 2 is a top plan view thereof;

FIG. 3 is a bottom plan view thereof;

FIG. 4 is a rear edge view thereof;

FIG. 5 is a front edge view thereof;

FIG. 6 is a left end perspective view thereof;

FIG. 7 is a right end perspective view thereof; and,

FIG. 8 is an alternative perspective view thereof, showing the instrument in use.

The broken line showing is for illustrative purposes only and forms no part of the claimed design.
